KATSUHARU HIBI, OF TOKYO, JAPAN.

INTERNAL-COMBUSTION ENGINE.

1,264,518.

Specification of Letters Patent. Patented Apr. 30, 1918.

Application filed March 23, 1917. Serial No. 156,941.

To all whom it may concern:

Be it known that I, KATSUHARU HIBI, subject of the Emperor of Japan, residing at No. 339 Ippongi, Kita-Shinagawa, Tokyo, Japan, have invented new and useful Improvements in Internal-Combustion Engines, of which the following is a specification.

This invention relates to improvements in internal combustion engines, and comprises the following parts and devices. By means of opening a valve, actuated either mechanically or automatically, a portion of the air in the cylinder is admitted into a first chamber connected with said cylinder during the compression stroke of the piston, and as the compression goes on the temperature of the admitted air rises, so that the fuel previously charged into this chamber, in such a proper quantity as will attain complete combustion with the air admitted into the chamber, will be ignited and exploded, either by the heat of compression of the air or by suitable ignition apparatus, thus maintaining the product of combustion within the first chamber at a far higher temperature and pressure than within the cylinder. In case the fuel supplied to this chamber proves insufficient to develop the required power, a supplementary charge of fuel is forced into a second chamber having a communication with the inside of the cylinder, through a passage of proper and suitable form. This fuel is stirred up by the inrush, through the passage of suitable form mentioned above, of a portion of the air from the cylinder into said second chamber, and is intermixed with the air as thoroughly as possible. Also, in case the fuel is in liquid state, the volatilization process is greatly accelerated. At the instant, or a little before or after as may be desired, the piston reaches its dead point, the valve between the first and second chamber is opened, thus interconnecting the two chambers. The forceful discharge of highly heated and highly compressed product of combustion from the first chamber forces the fuel and air in the second chamber into the cylinder, and the non-combusted fuel burns in the cylinder, where it expands together with said highly heated gases and then does its work.

The object and the special feature of the invention lie in the utilization of a large portion of the time required in the compres-

sion stroke of the piston, in previous heating of the fuel, and particularly, when liquid fuel is employed, its vaporization process is accomplished mostly in the course 60 of the compression stroke of the piston, unlike the Diesel engine, wherein the vaporization process of liquid fuel takes place only after the fuel is admitted into the cylinder, i. e., the two processes of vaporization and 65 combustion of the fuel are made to take place in a comparatively short time. Dispensing with the employment of a special air-compressor of high pressure for injecting the fuel into the cylinder, the present 70 invention reduces the construction to an extreme simplicity, yet it effects the vaporization of the fuel and its mixture with air as thoroughly as desired and attains a maximum thermal efficiency of an internal 75 combustion engine, by obtaining the compression necessary and ample for realizing such highest thermal efficiency, without the annoyance of premature explosion.

Referring to the drawings:—

Figure 1 is a vertical section showing the arrangement of the principal parts of a two-cycle internal combustion engine using liquid fuel.

Figs. 2 and 3 are enlarged sections of 85 part D of Fig. 1.

Fig. 4 is an enlarged plan view of part D. The following is a detailed description of the invention:—

Fig. 1 shows a part of a two-cycle internal combustion engine, wherein A is the cylinder cover; B, the cylinder; C, the piston; and D, the part constituting this invention. In Figs. 2, 3 and 4, when the piston makes its compression stroke, a portion of the air inside the cylinder is forced into the chamber 3 by opening the valve 2, due to the compressive action of the piston. The required fuel is previously charged into chamber 3, at the proper moment before or after the piston commences its compression stroke, by opening the valve 6, after passing through a duct 16 from the port 25, all shown in Figs. 3 and 4.

The quantity of the fuel should be so determined that the same will attain a good combustion with the air in chamber 3, leaving no deposit of remains of incomplete combustion, which would hinder the smooth operation of the engine. The temperature 105 of the air which has entered chamber 3 from the cylinder through 1 and valve 2

becomes higher and higher as the compression stroke of the piston progresses. At the same time the fuel in chamber 3 gets steadily heated if the same is in gaseous form, and if, in liquid state, is first vaporized and finally burns. It goes without saying that an ignition device may well be provided in chamber 3 if the degree of compression proves insufficient to cause combustion in the chamber. As soon as combustion takes place in chamber 3 an exceedingly high pressure results therein, causing the valve 2 to close and shutting off the communication between the cylinder and the chamber 3. In case the fuel supplied to chamber 3 alone proves insufficient against the load to be carried by the engine, another and independent supply of fuel is forced into chamber 7 from the passage 15 opening the valve 8, and is then deposited in the quarter marked 9. As to the admission of this latter fuel, it is not absolutely necessary to be made simultaneously with that for chamber 3, but it is to be adjusted to either lead or lag in accordance with the quality of the fuel. The air compressed in the cylinder by the piston is forced into the quarter 9, through 11 and 10. When the part 9 is filled with fuel, the inrush of the air stirs up the same and a thorough mixture results. Now, the valve 5 is opened at the instant, or a little before or after, the piston completes its compression stroke, then the highly heated and highly compressed gas in chamber 3 will force its way into the cylinder from 5 through 7, 9, 10 and 11. At the same time, the fuel and air existing in 7 will together be forced into the cylinder, wherein on account of the high temperature they burn completely, and expand together with the gases from chamber 3, thus accomplishing the work. The valve 5 should be left open until the piston ends its exhaust stroke. As the chamber 3 is filled with gases of combustion, so to wash it once with fresh air has a beneficial effect upon the next combustion. For this purpose a valve 4 is provided in chamber 3. The upper portion of 4 is connected through 12 to a fresh air reservoir, wherein is maintained a pressure a few pounds per square inch above the atmosphere, and at a period of the cycle at which the engine exhausts the valve 4 is opened to pass the air into chamber 3, and thence through 5, 7, 9, 10 and 11 into the cylinder, thus exhausting the gases of combustion from chamber 3 and filling the same with fresh air, which affords a cooling effect to the chamber 3. Valve 17 shown in Fig. 3 is a compressed air starting valve, admitting the compressed air for the starting from 24. By pressing 18, forcing the spring 23 and opening 17 the compressed air is admitted into the cylinder to start the engine, but this part has no bearing on the present

invention. Valves 4 and 5 are held in closed position by springs 19 and 20 respectively, and, at the proper moment as described above, they are opened by a suitable contrivance like a lever, etc., which presses 13 or 14 and overcomes the tension of the springs. Valves 6 and 8 are closed by springs 22 and 21 respectively, and opened by the pressure of the fuel being admitted from 25 or 15, but they can, of course, be so constructed as to be opened at the proper moment by providing a special lever, as with the valves 4 and 5.

The fuel supplied to chamber 3 and that supplied to chamber 7 need not be necessarily of the same quality. For instance, into the chamber 3 may be supplied a fuel like petroleum, which is comparatively easy to vaporize and burn, whereas in chamber 7 may be used a fuel which is comparatively difficult to volatilize and ignite, like tar-oil. By such an arrangement, at a comparatively low degree of compression, and even without employing a special ignition device, the petroleum in chamber 3 may first be burned by the heat of compression only and then the tar-oil in chamber 7. Should a still lighter oil, like gasoline, be used in chamber 3, the above described action may be effected even at a much lower degree of compression. It must not be forgotten, however, that the lowering of compression is detrimental to the heat efficiency of an internal combustion engine, and therefore, it is important to retain a proper degree of compression in order to secure a good thermal efficiency, aside from the consideration of ignition and explosion of a fuel by its own heat due to compression. But in the case where there are special conditions imposed, such as lowering of the manufacturing cost or limitation to the weight of the engine, etc., it may often be found advantageous to lower the compression as much as possible by employing in chamber 3 a fuel which is easy to volatilize and burn. Again, when the fuel supplied to chamber 7 is easy of volatilization and combustion, it is not necessary to have the same charged in chamber 7 in advance, but the same may be injected by opening 8 when the gases highly heated and highly compressed are discharged from chamber 3 by opening 5. Unlike the case previously described, to inject the fuel by means of valve 8 requires work against considerable pressure, yet in this instance the construction is extremely simplified as one may design the engine considering chamber 7 simply as a part of the cylinder, and entirely dispensing with such special passes as 9 and 10.

As has been made clear from the above description, the principal advantages derived from this invention are as follows:

Firstly:—The fuel has no necessity to 130

work against any considerable pressure, being admitted into the chambers at the instant, or a little before or after, the piston begins its compression stroke.

5. Secondly:—In case liquid fuel is employed, the same can be given ample time for vaporization.

Thirdly:—Since the fuel can be injected into the cylinder by means of the pressure 10 created by the combustion in chamber 3, there is no necessity for storing high pressure air for fuel injection by providing a special high pressure air compressor.

Fourthly:—By supplying a fuel comparatively easy to vaporize and ignite into chamber 3, and one comparatively difficult to do so into chamber 7, the combustion of fuel in the cylinder can be attained by the heat of compression only without unduly raising 20 the pressure in the cylinder.

Claims:

1. In an internal combustion engine, the combination of a working cylinder, a piston operating in said cylinder, a chamber adapted to be placed in direct communication with the cylinder, means for permitting compressed air to enter the said chamber from the cylinder during the compression stroke of the piston, means for introducing 25 a charge of fuel into the said chamber toward the end of the compression stroke, a second chamber adapted to communicate with the first chamber and with the cylinder, means for introducing a fuel charge 30 into the second chamber, and means for permitting flaming products of combustion to pass from the first chamber through the second and into the cylinder at the proper time during the compression stroke.

40. 2. The method of operating internal combustion engines having two chambers communicating with each other and with the working cylinder, which consists in igniting a combustible mixture in one of the chambers, and vaporizing a charge of fuel in the other chamber and injecting it into the cylinder by passing the flaming products of combustion from the first-mentioned chamber through the second one into the cylinder.

45. 3. The method of operating internal combustion engines having two chambers communicating with each other and with the working cylinder, which consists in compressing air in the cylinder, igniting a mixture of air and a volatile and readily combustible fuel in one of the chambers, and vaporizing a charge of a less volatile and more difficult combustible fuel in the other chamber and injecting it into the cylinder 50 by passing the flaming products of combustion from the first-mentioned chamber through the second one into the cylinder.

60. 4. The method of operating internal combustion engines having two chambers communicating with each other and with the

working cylinder, which consists in compressing air in the cylinder, introducing a fuel charge into one of the chambers, admitting compressed air from the cylinder into the said chamber during the compression stroke, firing the mixture in the said chamber at a predetermined time during the compression stroke, and vaporizing a charge of fuel in the other chamber and injecting it into the cylinder by passing the flaming products of combustion from the first-mentioned chamber through the second one into the cylinder.

5. The method of operating internal combustion engines having two chambers communicating with each other and with the working cylinder, which consists in igniting a combustible mixture in one of the chambers, vaporizing a charge of fuel in the other chamber and injecting it into the cylinder by passing the flaming products of combustion from the first-mentioned chamber through the second chamber into the cylinder, and forcing a scavenging charge through the both chambers into the working cylinder 90 at a period of the cycle when the engine exhausts.

6. The method of operating internal combustion engines having two chambers communicating with each other and with the working cylinder, which consists in compressing air in the cylinder, igniting a mixture of air and a volatile and readily combustible fuel in one of the chambers, vaporizing a charge of a less volatile and more difficult combustible fuel in the other chamber and injecting it into the cylinder by passing the flaming products of combustion from the first-mentioned chamber through the second one into the cylinder, and forcing 100 a scavenging charge of air through said chambers into the working cylinder at a period of the cycle at which the engine exhausts.

7. The method of operating internal combustion engines having two chambers communicating with each other and with the working cylinder, which consists in compressing air in the cylinder, introducing a fuel charge into one of the chambers, admitting compressed air from the cylinder into the said chamber during the compression stroke, firing the mixture in the said chamber at a predetermined time during the compression stroke, vaporizing a charge of fuel in the other chamber and injecting it into the cylinder by passing the flaming products of combustion from the first-mentioned chamber through the second one into the cylinder, and forcing a scavenging charge 110 of air through the chambers and into the working cylinder at a period of the cycle at which the engine exhausts.

8. In an internal combustion engine, the combination of a working cylinder, a piston

- operating in said cylinder, means for utilizing the compression stroke of the piston to compress and ignite a charge of fuel exteriorly of the cylinder, and means operable 5 by said ignited charge of fuel for igniting and injecting another charge of fuel into said cylinder, the second charge of fuel being less volatile and less combustible than the first charge of fuel.
- 10 9. In an internal combustion engine, the combination of a working cylinder, a piston operating in said cylinder, means for utilizing the compression stroke of said piston to compress and ignite a charge of fuel exteriorly of said cylinder, and means operable 15 by said ignited charge of fuel for igniting and injecting another charge of fuel into said cylinder.
- 10 10. In an internal combustion engine, the combination of a working cylinder, a piston operating in said cylinder, a chamber adapted 20 to be placed in direct communication with the cylinder, means for permitting com-

pressed air to enter the said chamber from the cylinder during the compression stroke 25 of the piston, means for introducing a charge of fuel into the said chamber toward the end of the compression stroke, a second chamber adapted to communicate with the first chamber and with the cylinder, means 30 for introducing a fuel charge into the second chamber, means for permitting flaming products of combustion to pass from the first chamber through the second and into the cylinder at the proper time during the 35 compression stroke, and means for flushing said chambers and said cylinder with air at a period at which the engine exhausts.

In testimony whereof I have signed my name to this specification in the presence of 40 two subscribing witnesses.
